(57) **CLAIM**

The ornamental design for a spare tire mounting tool, as shown and described.

DESCRIPTION

FIG. 1 is a top, front left perspective view of a spare tire mounting tool according to the invention;

FIG. 2 is an enlarged detail view of the handle end thereof;

FIG. 3 is a left elevational view thereof, the right elevational view being a mirror image;

FIG. 4 is a front elevational view thereof;

FIG. 5 is a rear elevational view thereof;

FIG. 6 is a top plan view thereof; and,

FIG. 7 is a bottom plan view thereof.
